COLLAPSIBLE PROTECTIVE CANOPY

Helen Martinson, Chicago, Ill.

Application April 4, 1934, Serial No. 718,944

6 Claims. (Cl. 65—16)

The present invention pertains to protective covers or canopies of an expandable and collapsible nature, having for its primary object the provision of a dust-proof, preferably transparent, canopy adapted to be placed over articles of food or over a stack of plates or other dishes, drinking glasses, etc. and which, when collapsed on the shelf of the dealer or in the linen drawer or china closet of the housewife, occupies a minimum of space.

Features of the invention are the low cost of manufacture, economy of space required by a reserve stock, attractive appearance and efficiency as a protection against dust and the access 15 of air whereby articles of food, such as cakes, rolls and the like, are kept in a normal condition, not readily subject to drying out or the absorbing 20 of moisture from humid air; whereby dishes, glassware, silver and the like are protected from dust and flies; and whereby flowers, fruit and such are protected from draft to avoid withering while subjected to cold whether adjacent an open 25 window or under artificial refrigeration.

In order that the invention may be readily 30 understood a preferred embodiment of the same is hereinafter described in connection with the accompanying illustrated drawing, wherein

Fig. 1 represents a strip of material creased along lines of fold;

Fig. 2 is a top plan of the canopy when folded; Fig. 3 is a bottom plan; Fig. 4 is a view of the expanded canopy; and Fig. 5 is a section on the line 5—5 of Fig. 4.

It is to be understood that the essential features of the invention may be embodied in other forms differing from that illustrated and hereinafter described in the relative locations of the lines of fold and the number of such lines, resulting in a finished article of different contour; 40 wherefore the particular embodiment here illustrated and described is to be taken as typical and not as limiting the invention other than is required by the prior art.

Referring to the drawing, there is shown in 45 Fig. 1 an elongated rectangular strip of material 11, preferably transparent such as "Cellophane", which may be gummed along one end as indicated at 12. The broken line 13 represents a medial line of crease or fold extending longitudinally of the strip midway between its sides. The dot and dash lines 14 which extend transversely of the sheet represent lines of crease or fold parallel to each other and at right angles or normal to the line 13; while dot lines 15 extending diagonally or at an oblique angle to the

medial line 13 also represent parallel lines of crease or fold intersecting the lines 13 and 14 at common points 16. The normal and oblique lines of each set preferably extend from edge to edge of the sheet and intersect the medial line 5 at a series of equally spaced points common to all three, the medial line thus bisecting both the normal and oblique lines into parts preferably equal.

The finished article may be formed by folding 10 along the medial line 13 and also along the transverse lines 14 in the same direction, that is to say, all of said folds would be convex as related to the surface of the flat sheet; and a subsequent folding along the oblique lines 15 would be in the 15 opposite direction, that is to say, such oblique folds would be concave as related to the surface of the sheet.

When the folding is completed, there is formed a flat product of polygonal contour, here shown 20 as octagonal, having substantially identical upper and lower faces constituted of overlapping folded portions presenting a geometrical outline of general swastika design, most clearly shown in Fig. 3. The ends 12 of the sheet now lie in juxtaposed position overlapping to the extent of the distance between the left hand end 12 of Fig. 1 and the adjacent line 14 and they are secured together by the moistening of the gummed end. The opening up of the folds constituting the 30 upper face of the article may be prevented by securing the same together in any way but preferably by applying thereover a polygonal sticker 17 having a shape, here shown as octagonal, corresponding to that of the folded body itself but 35 of smaller size so that the outline of said sticker will correspond to lines connecting the extreme corners of each folded-over portion. This is most clearly shown in Fig. 2. The sticker 17 may carry an ornamental imprint or the trade- 40 mark or name of the manufacturer.

The folds of the lower face being unsecured, they may be opened up and the article expanded into inverted cup form of polygonal cross section with vertical walls as shown in Fig. 4; thus constituting a canopy which may be dropped over dishes, glassware, silver and articles of food for their protection against air interchange, dust and the like.

Obviously the size of the canopy may be varied 50 to suit different needs by change in dimensions of the sheet of material and the relative horizontal and vertical dimensions and the contour may be modified by changing the relative disposition of the lines of fold. The material employed may be 55

opaque or semi-transparent paper or a fully transparent material, such as "Cellophane". The articles, when formed and in the collapsed condition illustrated in Figs. 2 and 3, occupy no more space than a folded paper napkin, and a large quantity of the same can be held in reserve for sale or use in a very small space. The simplicity of construction and inexpensiveness of material make for economy of manufacture and consequent low price at which it may be sold.

I claim:

1. A protective device of the character described comprising an elongated sheet of material folded along a medial line and along other lines 15 normal to the first and along other lines oblique to the first, all lines of fold extending from edge to edge of the sheet, the normal and oblique lines folded to face in opposite directions and crossing each other and the medial line at a common point, the ends of the sheet secured together and the folds at one side of the medial line secured against opening, whereby is produced a flat device which upon opening up of the unsecured 20 folds will be expanded into inverted cup form of polygonal section with vertical walls.
2. A protective device of the character described comprising an elongated sheet of material folded along a single medial line and along other lines normal to the first and along other 30 lines oblique to the first, all lines of fold extending from edge to edge of the sheet, the normal and oblique lines folded to face in opposite directions and crossing each other and the medial line at a common point, the ends of the sheet secured together and the folds at one side of the medial line secured against opening, whereby is produced a flat device which upon opening up of the unsecured 35 folds will be expanded into inverted cup form of polygonal section with vertical walls.
3. A protective device of the character described comprising an elongated sheet of transparent material folded along a medial line and along other lines normal to the first and along other 45 lines oblique to the first, all lines of fold extending from edge to edge of the sheet, the normal and oblique lines folded to face in opposite directions, the three lines of fold intersecting only at a series of points intermediate the length 50 of each and equally spaced longitudinally of the sheet, the ends of the sheet secured together and the folds at one side of the medial line secured against opening, whereby is produced a flat device which upon opening up of the unsecured 55 folds will be expanded into inverted cup form of polygonal section with vertical walls.
4. A protective device of the character described comprising an elongated sheet of "Cello-

phane" folded along a single medial line and along other lines normal to the first and along other lines oblique to the first, all lines of fold extending from edge to edge of the sheet, the normal and oblique lines folded to face in opposite directions and crossing each other and the medial line at a common point, the ends of the sheet secured together and the folds at one side of the medial line secured against opening, whereby is produced a flat device which upon opening up of the unsecured folds will be expanded into inverted cup form of polygonal section with vertical walls.

5. A protective device of the character described comprising an elongated sheet of "Cellophane" material folded along a single medial line and along other lines normal to the first and along other lines oblique to the first, all lines of fold extending from edge to edge of the sheet, the normal and oblique lines folded to face in opposite directions and crossing each other and the medial line at a common point, the ends of the sheet secured together and the folds at one side of the medial line secured against opening, whereby is produced a flat product of polygonal 25 contour having substantially identical upper and lower faces constituted of overlapping folded portions presenting a geometrical outline of general swastika design, and means to secure the overlapping folds of the upper face against opening, 30 the folds of the lower face unsecured whereby to permit the device to be opened up and expanded into inverted cup form of polygonal section with closed top and open bottom and vertical walls.

6. A protective device of the character described comprising an elongated sheet of transparent material creased along a medial longitudinal line and also along transverse lines both normal to and diagonally of and intersecting the medial line at a longitudinally spaced series of 40 points common to all three sets of lines, said sheet folded on the medial line and also along the transverse lines, the direction of fold alternating as between the normal and diagonal lines, and the two ends of the material joined, whereby 45 is formed a flat product of octagonal contour having substantially identical upper and lower faces constituted of overlapping folded portions presenting a geometrical outline of general swastika design, and a correspondingly shaped 50 octagonal sticker centrally attached to the upper face whereby to secure the overlapping folds against opening, the folds of the lower face unsecured whereby to permit the device to be opened up and expanded into inverted cup form of octa- 55 gonal section with closed top, open bottom and vertical walls.

HELEN MARTINSON.
